UNITED STATES PATENT OFFICE.

SAMUEL H. TERRY, OF GUTHRIE, MISSOURI.

TRACTION-ROPE RAILWAY.

SPECIFICATION forming part of Letters Patent No. 247,523, dated September 27, 1881.

Application filed November 23, 1880. (No model.)

To all whom it may concern:

Be it known that I, SAMUEL H. TERRY, of Guthrie, in the county of Callaway and State of Missouri, have invented a new and useful 5 Improvement in Traction-Rope Railways, of which the following is a specification.

My improvements relate to railways in which the cars are driven by a traction-rope moving in a tunnel or gutter placed below the ground. 10 The difficulties experienced in operating such railways, and which my improvements are calculated to obviate, have arisen from the open gutter and at the intersections and crossings of the railways.

15 My invention consists in a gutter or tunnel of novel construction, which allows water to pass off readily and permits flushing to remove refuse; in independent swinging covers which close the top of the gutter closely and are 20 opened in succession as the cars move along the track; in clutches of novel construction attached to the cars, and in certain other features, which will be described in detail hereinafter.

In the accompanying drawings, Figure 1 is 25 a plan view, showing a section of a railway embodying my invention. Fig. 2 is a vertical longitudinal section of the railway and a car. Fig. 3 is a vertical transverse section of the road and car, looking at the back of the clutch. 30 Fig. 4 is a cross-section of the road and end view of the car. Fig. 5 is a horizontal section of the clutch on line $x-x$ of Fig. 6. Fig. 6 is a vertical section of the clutch, with the road shown in section at a crossing; and Fig. 7 is a 35 cross-section of the road on line $y-y$ of Fig. 1.

Similar letters of reference indicate corresponding parts.

At $a-a$ are shown the rails of the road, laid upon cross-ties, as usual, and $a'-a'$ are the rails 40 of a cross-track.

B B' are the gutters or tunnels of the respective roads, placed midway between the rails, with the upper side level, or nearly so, with the pavement, so as to offer no obstruction.

45 The construction of the gutter is the same in both tracks. Preferably they consist, as shown, of side pieces, $c c'$, secured or laid upon plates d , that rest on cross-ties of the track; but, if desired, the sides and bottom may be cast in 50 a single piece. Beneath the ties is a water-way formed by a concave plate or casting, d' ,

which is to have suitable outlets, as shown at d'' , connected with a sewer, and the bottom plates, d , of the gutter have openings at intervals to allow escape of water and refuse to the 55 water-way.

At $e e'$ are the traction-ropes, extending through the gutters. These are supported above the bottom plates, d , by rollers f , placed at suitable intervals and at suitable angles, according to the direction of the track. These 60 ropes are to be driven by stationary engines arranged in any desired manner. At the crossing the under ropes pass beneath and the upper rope between beveled guide-plates g , which 65 act to relieve the clutches at the crossing, as hereinafter described. To prevent the rope rising by the strain, holders g' , Figs. 1 and 7, are placed at intervals, which consist of bars pivoted at their mid-length within the gutter, 70 in position for being turned with either end over the rope, the ends having beveled projections, by which the clutches move the holders g' as the car passes.

The gutters B are covered by plates h , of 75 suitable length, which fit in rabbets formed in the upper edges of the sides $c c'$, so that the plates lie flush; and the plates are separately pivoted to lugs formed at intervals on the rabbed edge of one side, c or c' , so that the covers open upward. These covering-plates may, however, be fitted to swing sidewise, or slide bodily sidewise, instead of swinging upward; and I do not limit myself in that particular. At the intersection of the tracks the covering- 80 plate h' is hinged to the adjacent end of plate h , so as to swing thereon to allow the clutch to pass through one gutter, and swings with the plate h , to which it is hinged, to allow the clutch to pass in the other gutter. The gutter 85 is thus covered at the intersections, and this construction is applicable to any angle of crossing or junction.

The cars are connected to the rope by clutches placed beneath the cars and fitted for operation from the platforms to catch and release the rope, as next described.

At C is represented a car, supported on the track by its wheels $i i$. Beneath the car is a frame composed of rods k , fixed at their ends 90 to heads k' , and sustained by a bracket, l , at one end of the frame, and a link, l' , at the

other end. The connection between bracket *l* and the head *l'* at that end is made by a flexible joint, *m*, which may, if preferred, be a ball and socket, the connection of the bracket with the car being a knuckle-joint. The link *l'*, at the other end, is attached to the car-bottom by a knuckle-joint, and slotted at its outer end to receive pins projecting from head *l'*. This construction allows vertical and transverse movement of the frame on the joint *m*, so that the clutching mechanism carried by the frame shall not be thrown out of place by oscillations of the car caused by irregularities of the track.

Upon rods *k* is fitted a slide-block, *n*, and around the middle rod is a spiral or other spring, *n'*, tending to force the block *n* toward the mid-length of the car.

To the block *n* is fixed a standard, *o*, to which is hung by a knuckle-joint, *o'*, at their mid-length, a similar standard, *p*. The lower ends of the standards *o* *p* extend into the gutter *B* and terminate at opposite sides of the traction-rope. These ends are mortised to receive the clutching devices, which, as shown, consist of wedges *q* *q'*, Fig. 5, fixed on arms *q'*, that project from a spindle, *r*, fitted in bearings on the back of the standards *o* *p*, so that the wedges can slide in and clamp the rope between them, and outward to release the rope. The spindle *r* has also an arm, *r'*, from which a rod, *s'*, projects to and is joined to a slide, *s*, that is hung between the standards by a link, *s''*, so as to be capable of vertical movement. The lower end of slide *s* terminates in a flange extending horizontally between the standards above wedges *q*. Through its upper end extends one fork of a forked rod, *t*, the other fork of which is sustained in the fixed standard *o*. The forked rod *t* passes loosely through the standard *o* and slide *s*, so as to be adapted to raise or lower the latter. The forward end of the rod is sustained by a hanger attached to the car-platform and carries a toothed segment, *t'*, that is engaged by a pinion, *u*, on the lower end of the brake-shaft *u'*. From the lower part of standard *o* inclined flanges *v* project in the direction of the gutter and terminate below the hinged covers, so as to raise the covers successively as the car moves along. A spring-*50* arm attached to the standard may be used to press the covers down after the clutch has passed.

The operation is as follows: To connect and start the car the brake-shaft *u'* is turned to turn pinion *u* and the segment *t'*, and rod *t* being thereby turned, the slide *s* is moved down and spindle *r* thereby turned to throw wedges *q* into the mortises of the standards and clamp the rope. This movement of the wedges being in the direction the rope is moving, the wedges are drawn tightly, and the standard *p* being hinged to the standard *o*, its lower end is kept toward the said standard *o* by the slide *s*, whose wedge-shaped upper end, when it is depressed, wedges apart the correspondingly-shaped upper ends of said standards. The

standard *p* will give way to the draft of the rope and prevent shock by the block *n* having a yielding engagement through spring *n'* with the car. The first action of the rope is to move slide *n* forward on rods *k* against the spring, which, being of suitable strength, takes the tractive power partially until the inertia of the car is overcome, and it moves at the same speed as the rope. As the car moves along, the forward flange, *v*, passing beneath the covers, opens them in succession and holds them until the standards pass, the rear flange, *v*, allowing the covers to drop gradually. When the car reaches a crossing the bottom flange of slide *s* comes in contact with the top of guides *g*, said slide being thereby raised, the wedges thrown back, and the rope thereby released. While the car is passing the standards *o* *p* also ride upon the guides *g*, and being lifted thereby pass over the crossing cable, the flexible connection of the frame of rods *k* with the car permitting the same. As soon as the slide and standards pass the guides those parts come down by their weight in readiness to clamp the rope. To obtain space for this operation the lower rope may be depressed and held down by rollers at the crossing. To release the clutch from the rope the brake-shaft will be turned back, which will throw back the wedges and raise the slide. The slide *s* may be fitted with projections, preferably inclined, to engage the lower ends of the standards as it rises and spread them apart. The brake-shaft will be arranged in such manner that its first movement shall release the clutch, as mentioned, and a further movement apply the brakes. The covers *h* prevent dirt and mud from entering the gutters, and serve also to prevent wheels of vehicles from entering the gutter. The water-way serves to keep the gutter free from water, and permits the flushing of the gutter with water to clean it.

I do not limit myself to the details of construction exactly as described, as they may be varied within the scope of my invention.

I am aware that cables have been used with tubes longitudinally slotted on top, and with longitudinal timbers forming a gutter beneath it; also, that troughs provided with flexible hinged valves or covers are not broadly new; but

What I claim as my invention is—

1. In traction-rope railways, the gutters or tunnels *B*, for the traction-rope, having apertured bottom *d*, and provided with water-way *d'* beneath the bottom and under the cross-ties, substantially as and for the purposes set forth.

2. The compound hinged covering-plates *h*', combined with the intersecting or crossing gutters *B'*, substantially as shown and described, for the purposes specified.

3. In traction-rope railways, the pivoted bars *g'*, combined with gutter *B* and traction-rope *e*, when fitted for movement by the clutch of a passing car, as specified.

4. The beveled guides *g*, combined with the

traction-ropes $e e'$, when placed to relieve the rope from the clutches of a passing car, substantially as shown and described.

5. The frame of rods k , heads k' , spring-slide n , carrying the clutching mechanism, bracket l , having the flexible joint m , and link l' , combined together and with the car C, substantially as shown and described.

6. The standard o , provided with inclined flanges v and carrying clutches at its lower end, combined with a car, a gutter or tunnel, B, having movable covering-plates h and traction-rope passing through the gutter, substantially as shown and described.

15 7. In traction-rope railways, the clutching mechanism consisting of fixed standard o , pivoted standard p , wedges q , spindle r , carrying

the wedges, slide s , connected to the spindle, forked rod t , segment t' , pinion u , and operating-shaft u' , combined together and with the car, substantially as shown and described, for operation as specified.

8. In traction-rope railways, the combination of a gutter or tunnel having its upper side closed by a cover arranged in short hinged sections, a moving traction-rope within the gutter, and a car or cars provided with devices for clutching the rope and opening the sections of the gutter-cover as the car passes, substantially as shown and described.
